CLAIM

The ornamental design for a battery connector as shown and described.

DESCRIPTION

FIG. 1 is a front, left, and top perspective view of a battery connector in accordance with our new design;

FIG. 2 is a front, right, and top perspective view thereof;

FIG. 3 is a front, left, and top perspective view thereof;

FIG. 4 is a rear, right, and top perspective view thereof; and,

FIG. 5 is an enlarged detail view of area 5 circumscribed within FIG. 1.

The evenly spaced broken lines depict the portions of the battery connector that form no part of the claimed design. The evenly spaced broken lines illustrating a saw depict environmental subject matter that forms no part of the claimed design. The dot-dash-dot broken lines depict the boundaries of the claim and form no part thereof. The dash-dot-dot-dash broken lines in FIGS. 1 and 5 denote the boundaries of the detail area and form no part of the claimed design. The portions outside of the portion circumscribed by the dash-dot-dot-dash lines in FIGS. 1 and 5 form no part of the claimed design.
